UNITED STATES PATENT OFFICE.

GEORGE W. STIMPSON AND JAMES B. NEEDHAM, OF SAN FRANCISCO, CALIFORNIA.

ADJUSTABLE SEAT-RAIL FOR VEHICLES.

SPECIFICATION forming part of Letters Patent No. 248,363, dated October 18, 1881.

Application filed May 20, 1881. (No model.)

To all whom it may concern:

Be it known that we, GEORGE W. STIMPSON and J. BENJAMIN NEEDHAM, of the city and county of San Francisco, in the State of California, have made and invented a new and useful Adjustable Seat-Rail for Vehicles, of which the following is a full and complete specification, reference being had therein to the accompanying drawings.

10 The object of our invention is to provide carriage and wagon makers with a seat-rail which they can apply to any size of seat, and thereby avoid the expense and labor of making special rails for different lengths of seats.

15 The improvement which constitutes our invention consists in making the side irons and the back part of the rail in separate pieces or sections, which can be readily put together and adjusted to form an adjustable rail for any size 20 of seat. The same can be readily applied without the extra labor and trouble of working out or altering rails to suit any special length of seat, and they can be supplied in a condition to be used by the trade on any size 25 of vehicle-seat at a reduced cost, and ready to be attached in place without requiring special alteration and adjustment.

In the accompanying drawings we have shown in Figure 1 the application of our improvement rail to a buggy-seat, and in Figs. 2, 3, 30 and 4 the parts of the rail in detail, and the means for securing it in position on the seat.

We make the side irons, A A, of the usual shape and size; but instead of forming them 35 in one piece with the back B we make the latter piece a separate and independent part, to have the side pieces, A, secured to it when the rail is fixed in place on the seat. The same size of side irons, A, can be employed with different lengths of back-rails, so that the sides 40 A can be worked out of uniform size; but the backs can be furnished with them of several graduated lengths, according to the standard lengths of vehicle-seats.

45 Manufacturers can readily adapt this rail to any length of seat by simply changing or regulating the length of the back-piece B, and then joining and securing the side pieces, A, to it.

While the sides A are worked out of 50 wrought-iron, the backs B may be made of malleable iron, to reduce the cost of manufacture; or the back, being a simple straight piece of metal, can be easily and quickly worked out of wrought metal by wagon-makers, if they so

prefer, and made longer or shorter, according 55 to the length of rail required for a particular size of seat. To join and firmly unite these parts together, we carry the ends of the side irons, A, at the corners around to the back a sufficient distance to give a length for a rabbet, a, at each corner, and then we provide a similar rabbet, b, at each end of the back B, so that the adjacent ends, when placed together, shall properly overlap and form a close, smooth, and strong joint, and then, by means 60 of small screws or bolts c, we secure the parts together. These screws may be provided with heads to serve as buttons for the side leathers when the rail is applied to a vehicle with a top and curtains.

The rail is secured and supported in place around the seat by the small uprights D D, through which the bolts e pass and are carried through into the rail above. These bolts work through slots f in the ends of the upright irons 70 D, so as to permit the rail to be adjusted and set out more or less from the side of the seat-body, as may be desired.

The rail is secured and supported in place around the seat by the small uprights D D, through which the bolts e pass and are carried through into the rail above. These bolts work through slots f in the ends of the upright irons 75 D, so as to permit the rail to be adjusted and set out more or less from the side of the seat-body, as may be desired.

Such rails can be supplied to the trade in a form and condition to be directly applied to 80 the several regular sizes of seats, as well as to any special sizes that makers may be called upon to turn out, and the time and labor now required to work up or alter a rail for a special application, or for use in repairing vehicles, are dispensed with.

Such rails can be supplied to the trade in a form and condition to be directly applied to 85 the several regular sizes of seats, as well as to any special sizes that makers may be called upon to turn out, and the time and labor now required to work up or alter a rail for a special application, or for use in repairing vehicles, are dispensed with.

We are aware that seat-rails for vehicles have been made before our invention with tubular angle-couplings for uniting the side and back rails; also, that side rails have been 90 rabbeted to wood backs. Such devices we do not claim.

Having thus fully described our invention, what we claim, and desire to secure by Letters Patent, is—

A seat-rail for vehicles formed of the angular side and back rails rabbeted and adjustably connected, in combination with supports, which are slotted to allow of said adjustment, and with the adjustable fastenings e, substantially as described.

Witness our hands and seals.

GEORGE W. STIMPSON. [L. S.]
JAMES B. NEEDHAM. [L. S.]

In presence of—

EDWARD E. OSBORN,
W. F. CLARK.
